UNITED STATES PATENT OFFICE

114,174

DESIGN FOR A VANITY CHEST OR ANALOGOUS ARTICLE

Hiram Felder, Roselle, N. J.

Application October 7, 1938, Serial No. 80,309

Term of patent 3½ years

To all whom it may concern:

Be it known that I, Hiram Felder, a citizen of the United States, residing at Roselle, in the county of Union and State of New Jersey, have invented a new, original, and ornamental design for a Vanity Chest or Analogous Article, of which the following is a specification, reference being had to the accompanying drawing, forming part thereof.

Figure 1 is a front elevational view of a vanity

chest or analogous article, showing my new design.

Figure 2 is a view in top plan thereof.

Figure 3 is a side elevational view.

I claim:

The ornamental design for a vanity chest or analogous article, as shown.

HIRAM FELDER.
